(57) **CLAIM**

The ornamental design for a wearable phototherapy apparatus for hair and scalp treatment, as shown and described.

DESCRIPTION

FIG. 1 is a perspective view of a wearable phototherapy apparatus for hair and scalp treatment showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top side elevational view thereof;

FIG. 7 is a bottom side elevational view thereof; and,

FIG. 8 is another perspective view thereof.
